UNITED STATES PATENT OFFICE.

FRANK HOLLAND, OF PORTERVILLE, CALIFORNIA.

TOBACCO-SMOKING PIPE.

SPECIFICATION forming part of Letters Patent No. 723,672, dated March 24, 1903.

Application filed February 1, 1901. Serial No. 45,649. (No model.)

To all whom it may concern:

Be it known that I, FRANK HOLLAND, a citizen of the United States, residing at Porterville, in the county of Tulare and State of California, have invented a new and useful 5 Tobacco-Smoking Pipe, of which the following is a specification.

My invention relates to tobacco-pipes; and the primary object thereof is to produce a 10 new and improved device of this character having the heel of the bowl thereof provided with an absorbent material exposed to atmospheric action, whereby the tar accumulating thereon may be evaporated to keep the 15 pipe-bowl free of all foreign matter.

A further object of the invention is to provide a pipe-bowl of a new and improved construction to obviate any liability of foreign matter, such as ashes or tar, entering the 20 mouthpiece.

Still further objects of the invention will appear as the nature of the same is more fully understood from the following description, taken in connection with the accompanying 25 drawings, forming a part of this specification.

In the drawings illustrating the preferred form of my invention, Figure 1 is a vertical sectional view of a pipe-bowl constructed in accordance with my invention. Fig. 2 is a 30 detail plan view of the absorbent material.

A designates a pipe-bowl open at both ends and of the usual size and configuration, the same comprising cylinders D, E, and F. The cylinder D is composed of paper, wood, or 35 other suitable material and constitutes the outer surface of the bowl. The cylinder F is composed of asbestos or other equivalent material and forms the inner surface of the bowl, obviating all liability of the interior of 40 the bowl being injured by fire. The cylinder E is composed of wood or other equivalent material and is interposed between the cylinders D and F to give to the pipe-bowl a rigidity sufficient to obviate all liability of its 45 becoming casually broken. The pipe-bowl is provided with an aperture J for the reception of the stem.

H designates a plug adapted to be fitted in the lower end of the bowl A and is provided 50 with a central vertical passage B, communicating through the medium of a horizontal passage with the aperture J. The plug has

the lower end thereof provided with a recess C of a diameter greater than that of the passage B. The recess C is adapted to receive 55 an absorbent material to take up all the tar which may accumulate in the passage B, and owing to the fact that the outer surface of the absorbent material is exposed to atmospheric action the tar accumulated by the same 60 will be readily and quickly evaporated.

G designates a disk of asbestos adapted to rest upon the plug H to retain the tobacco within the bowl against casual entrance to the passage B. The disk is provided with a 65 central aperture or apertures of a diameter sufficient to permit of the entrance of the smoke into the passage B and then through the aperture to the stem, but not to permit of the entrance of tobacco therein. 70

The absorbent material comprises a plug I of two or more layers of felt or any other suitable material and is adapted to occupy the recess C. The position of the plug I within the recess C places the upper surface 75 thereof in position to accumulate all foreign matter entering the passage B and places the lower or outer portion thereof in position to be exposed at all times to atmospheric action, whereby all moisture accumulated by the 80 plug will be evaporated, keeping the smoke free from obnoxious fluids and poisonous gases and also greatly obviating the necessity of frequently replenishing the absorbent material, the layers of which may be easily removed and replaced by fresh ones. The recess C being of a diameter greater than that 85 of the passage B forms a shoulder, against which the plug I is securely pressed and in which position the plug closes the heel of the 90 bowl A. It will be perceived that the exposition of the absorbent material to atmospheric action will evaporate the tar accumulated by the absorbent material, and thereby render the pipe-bowl free of all foreign substances. 95

It is obvious from the above description, taken in connection with the accompanying drawings, that I provide a pipe-bowl and absorbent of a new and improved character and also that the pipe is cheap, durable, and efficient. It may be further stated that as the stem does not project into the passage B all liability of foreign matter accumulated in 100

said passage below the horizontal passage entering the pipe-stem is obviated.

Having thus fully described the invention, what is claimed as new is—

- 5 1. A pipe comprising a bowl, and a pad of absorbent material arranged in the base of the bowl with its lower end exposed to the atmosphere.
- 10 2. A pipe comprising a bowl, a plug in the base of the bowl formed with a recess, and a pad of absorbent material arranged in the recess with its lower end exposed to the atmosphere.
- 15 3. A pipe comprising a bowl, provided with a stem-receiving opening, a plug in the base of the bowl formed with vertical and horizontal passages and a recess, and a pad of absorbent material arranged in the recess with its lower end exposed to the atmosphere.
- 20 4. A pipe comprising a bowl constructed of cylinders of asbestos, wood, and paper, and provided with a stem-receiving aperture, a

25 plug mounted in the bowl and provided with a vertical passage, and a horizontal passage in alignment with the aperture, said plug being provided with a recess, an asbestos disk mounted in the bowl and resting upon the plug, and an absorbent material secured in the recess, and having a portion thereof exposed to atmospheric action.

30 5. A pipe comprising a bowl, means for supporting the tobacco within the bowl, and a pad of absorbent material arranged in the base of the bowl with its lower end exposed to the atmosphere.

35 6. A pipe comprising a bowl, and a pad of absorbent material formed of removable layers, and arranged in the base of the bowl with its lower end exposed to the atmosphere.

FRANK HOLLAND.
